UNITED STATES PATENT OFFICE.

VICTOR L. TRUXALL, OF LATROBE, PENNSYLVANIA.

RAIL-JOINT.

SPECIFICATION forming part of Letters Patent No. 705,885, dated July 29, 1902.

Application filed February 18, 1902. Serial No. 94,614. (No model.)

To all whom it may concern:

Be it known that I, VICTOR L. TRUXALL, a citizen of the United States of America, residing at Latrobe, in the county of Westmoreland and State of Pennsylvania, have invented 5 certain new and useful Improvements in Rail-Joints, of which the following is a specification, reference being had therein to the accompanying drawings.

10 This invention relates to certain new and useful improvements in rail-joints, and relates more particularly to that class wherein the use of nuts and bolts is entirely dispensed with.

15 The invention has for its object the provision of a device of the above-described character that will be extremely simple in construction, strong, durable, comparatively inexpensive, and highly efficient in its use.

20 With the above and other objects in view the invention consists in the novel combination and arrangement of parts to be herein-after more fully described, and specifically pointed out in the claims.

25 In describing the invention in detail reference is had to the accompanying drawings, forming a part of this specification, and wherein like numerals of reference indicate like parts throughout the several views, in which—

30 Figure 1 is a perspective view of my improvements. Fig. 2 is a side elevation of the male member. Fig. 3 is a side elevation, partly in section, of the female member. Fig. 4 is an end view of the male member. Fig. 5 is a similar view of the female member.

35 In the drawings the reference-numeral 1 represents the male members, carrying enlarged web portions 2. The end of said male member of the rail is provided with a hook 3, 40 the body portion of which is in an approximately horizontal plane and carrying at its outer end a downwardly-extending portion 4. The inner edge of the said portion 4 is straight and its opposite edge beveled to form

45 a wedge-shaped end, as will be understood by reference to Fig. 2 of the drawings. The female rail member is indicated by the reference-numeral 5 and likewise carries the enlarged web portion 6, in which is formed the

50 horizontally-disposed recess 7 to receive the hook portion 3 of the male member. This re-

cess 7 is considerably wider than the hook and communicates at its rear end with the vertically-disposed contracted portion 8, in which the hook member is securely seated. 55

It will be seen that by bringing the two ends of the rails together the same will be easily joined without the necessity of placing the rails at an angle to one another, but simply bringing them together, allowing the hook 60 member to enter the enlarged recess 7 and then to be forced downwardly into the recess 8, forming a perfect joint between the rails.

The many advantages obtained by the use 65 of my improved rail-joint will be readily apparent from the foregoing description, taken in connection with the accompanying drawings.

It will be noted that various changes may 70 be made in the details of construction without departing from the general spirit of my invention.

Having fully described my invention, what I claim as new, and desire to secure by Letters Patent, is—

75 A rail-joint comprising abutting rail-sections each having the ends of their web portions enlarged, a centrally-arranged hook formed integral with one end of one of the rails, said hook having a horizontally-disposed body portion formed integral with the web and being of the same thickness thereof, said body portion of the hook being located 80 considerably below the head of the rail, carrying at its outer end a downwardly-curved 85 extension having one of its edges beveled, the other of said sections formed in its abutting edge with a centrally-arranged horizontally-disposed enlarged recess adapted to normally receive the body portion of the said hook, 90 said recess communicating at its rear end with a vertically-disposed contracted opening extending through the rail-base and adapted to receive the said downwardly-curved extension, substantially as described. 95

In testimony whereof I affix my signature in the presence of two witnesses.

VICTOR L. TRUXALL.
